ROTATABLE CONTAINER FOR TOILET ARTICLES

Sam H. Buskirk, Los Angeles, Calif.

Application August 15, 1955, Serial No. 37,439

Term of patent 14 years

(Cl. D86—10)

FIG. 1

FIG. 2

Fig. 1 is a top plan view of a rotatable container for toilet articles showing my new design;

Fig. 2 is a front elevational view; and

Fig. 3 is a perspective view, the broken line collapsible tube being for illustrative purposes only and comprising no part of the design of the present invention.

I claim:

The ornamental design for a rotatable container for toilet articles, substantially as shown and described.
